UNITED STATES PATENT OFFICE.

LENA BURKE, OF LEOMINSTER, MASSACHUSETTS.

DESIGN FOR A DOUBLE COLLAR-BUTTON.

41,982.

Specification for Design.

Patented Dec. 19, 1911.

Application filed June 14, 1911. Serial No. 633,208. Term of patent 3½ years.

To all whom it may concern:

Be it known that I, LENA BURKE, a citizen of the United States of America, residing at Leominster, in the county of Worcester and State of Massachusetts, have invented a new, original, and ornamental Design for Double Collar-Buttons; and I do declare the following to be a full, clear, and exact specification of the same.

My invention relates to a design for a "double collar-button," which is illustrated in the accompanying drawing, in which the figure is an elevation of a "double collar-button" showing my new design.

I claim,

The ornamental design for a "double collar-button."

LENA BURKE.
